UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK, A CORPORATION OF NEW YORK.

TYPEWRITING-MACHINE.

1,387,960.

Specification of Letters Patent. Patented Aug. 16, 1921.

Application filed November 11, 1918. Serial No. 261,971.

To all whom it may concern:

Be it known that I, FRANK H. ARMSTRONG, a citizen of the United States of America, and a resident of Auburn, county 5 of Cayuga, State of New York, have invented certain new and useful Improvements in Typewriting-Machines, of which the following is a full and clear specification.

10 This invention has relation to that class of case-shifts in which the case positions are obtained by shifting the segments up and down, and the object of this invention is to improve and simplify this type of mechanism, as more fully hereinafter set forth. The present improvements relate to that type of case-shift broadly covered by a co-pending application filed by me on the 3rd day of October, 1918, Serial No. 256,675.

15 In the drawings—

Figure 1 is a side elevation of the mechanism as it appears when the segment is at its upper, normal, position, the near side-wall of the frame being removed;

20 Fig. 2 is a similar view showing the parts adjusted to intermediate or "Cap." shift position;

25 Fig. 3 is a similar view showing the parts adjusted to its lowermost or "Fig." shift position; Fig. 4 is a detail perspective view hereinafter described;

30 Figs. 5, 6 and 7 are similar views to the foregoing, illustrating a modified form of my apparatus.

35 Referring to these drawings by reference-characters, 10 designates a segment-carrier which is arranged adjacent to the rear-wall of the frame and adapted to carry the usual segment. This segment-carrier is arranged to vertically slide on a pair of rods 12 rigidly mounted on the frame and one being arranged in each rear corner of the frame.

40 The segment-carrier is adapted to be pulled down to either its middle position or its lower position by means of a pair of arms 17 whose forward ends are rigidly affixed to a rock-shaft 18 journaled in the side-walls of the frame and extending 45 across the machine. The rear-ends of the arms 17 are pivotally and slidably connected to the segment-carrier by means of an open-ended slot formed in the rear-end of each arm and engaging a pin 19 affixed to 50 the outer face of the segment-carrier. These

arms 17 are arranged one at each side of the machine, and each arm is provided with a laterally-extending lug 20 whose upper working face inclines downwardly and forwardly.

55 The arms 17 are pulled downwardly to thus cause the segment to descend by means of shift-levers 21 and 22, these levers being, as usual, arranged in pairs adjacent to the side-walls of the frame, each pair lying in a vertical plane between an arm 17 and the adjacent side-wall of the frame. Each pair of shift-levers is pivotally mounted on a short bearing 23 extending inwardly from the adjacent side-wall of the frame, and 60 each lever carries at its rear end a forwardly-extending arm or tappet 24 so located and arranged that when the key-end of the lever is depressed this tappet will strike against the inclined upper side of 65 the adjacent lug 20 and thus swing the arm 17 downwardly against the action of a coil-spring 25, this spring serving to normally hold the segment-carrier in its upper position.

70 The tappet 24 on the shift-lever 22 is 70 shorter than the tappet on the companion lever 21, so that depression of said lever 22 will, by reason of the shorter arc the working-ends of its tappet describes, depress the arms 17 a less distance than when the shift-levers 21 are depressed, so that said shift-lever 22 may be used for pulling the segment down to its mid-position, while the companion lever 21 will be used for pulling the segment down to its third or lower 75 position. Each of these shift-levers is held in normal position by means of a suitable spring 26 and any suitable locking devices may be employed to lock either of the shift-levers in its lower position to thus hold the 80 segment in either of its lower-case positions.

85 In its normal uppermost position, the segment-carrier abuts against suitable adjustable stops (not shown) affixed to the frame, and in its lowermost or "Fig." shift position it likewise abuts against suitable adjustable stops on the base of the frame. The segment-carrier is positively locked in its normal position by means of a pair of 90 standing arms 32 whose lower-ends are 95 affixed to a rock-shaft 33 suitably journaled in the side-walls of the frame and extending entirely across the frame, one of these arms 32 being arranged at each side of the machine, in position to be 100 105 110

swung rearwardly to bring its upper-end under the top-lug 15 of the segment-carrier. This rockable frame (composed of the arms 32 and rock-shaft 33) is normally swung 5 rearwardly at its upper-end by means of a coil-spring 34. Each of the arms, at its rear edge, near its upper-end, is provided with an upwardly-facing stop-lug 35, which, when the arms 32 are swung forwardly to mid- 10 position, as shown in Fig. 2, are in vertical alinement with adjustable stop-screws 36 on the top-lugs 15 of the segment-carrier.

Pivottally attached to each of the arms 32 is a forwardly-extending link 37 which is 15 provided at its forward end with a slot 38 whose front-end is open. This slot engages the rock-shaft 18 and guides the link in sliding forwardly and backwardly. Each of these links at its upper forward corner is 20 provided with a lateral lug 39 which lies in the path of movement of the adjacent pair of shift-levers 21, 22, so that when either of said levers is depressed it strikes against the rear edge of this lug 39 and slides the link forwardly, thus swinging the lock-and-stop arms 32 forwardly against the action of their 25 springs 34.

At the point where the shift-levers impinge against lug 39, they are provided with 30 beveled faces 40 facing forwardly and downwardly. The beveled or cam face 40 on the lever 22 is shorter than the companion beveled face on the companion lever 21, so that when shift-lever 22 is depressed the rock- 35 arms 32 will be pulled forwardly a less distance than when the companion shift-lever is operated; and when either shift-lever is operated the rear-edge of lug 39 will pass upwardly in front of its co-acting beveled face 40 and engage a forwardly-facing locking shoulder 41 on the key-lever, to thus lock or hold the rockable stop-frame in its adjusted position until the key-lever returns to normal and thus releases the lug 39. When the 45 rockable stop-frame is thus shifted forwardly by means of the shorter cam 40, these arms will be in mid-position, *i. e.*, with their stop-lugs 35 in alinement with the stop-screws 36, so that as the arms 17 pull down 50 the segment the stop-screws will strike against said lugs 35 and thus arrest the segment-carrier in middle-case position. When the other shift-lever 21 is depressed to thus bring into action the longer one of the cam 55 surfaces 40, the rockable frame will be swung far enough forwardly to permit the stop-screws 36 and their supporting ears 15 to pass down behind the lugs 35, thereby permitting the segment-carrier to descend to 60 lower-case position.

In the modified form of my apparatus illustrated in Figs. 5, 6 and 7, it will be observed that the pivotal point 23 of the shift-levers is arranged, as in the other form, 65 at a point back of the impact-lug 20 carried

by the arm 17, and this impact-lug has its face inclining downwardly and forwardly also as in the other form. The differential arms or tappets 24 depend from the shift-levers at a point in front of the pivotal point 70 23 instead of extending forwardly from the pivotal point, as shown in the other form of my device. The cam arrangement for differentially rocking the stop-frame 32 consists in the present instance of a pair of 75 arms 45 inclining downwardly and forwardly from the rear ends of the shift-levers, one of these arms being longer than the other and each having its lower end rounded. The lower rounded ends of these arms, when in 80 normal position, lie immediately in front of the front inclined face of the lug 46 which is integral with the front lower end of an elongated lug 47 carried by the adjacent rocker-arm 32, this lug 46 being connected to 85 the main part 47 by an intermediate horizontal shelf-like part 48. When either one of the shift-levers is operated, the rounded nose of its depending arm 45 impinges against the beveled surface of lug 46 and 90 depresses the same and thus tilts the rockable stop-frame, and this tilting action continues until the rounded nose of the lever runs upon the top surface of the part 48, the action of the two levers 45 being respectively 95 illustrated in Figs. 5 and 6.

It is desirable that the lateral lug or tappet 39 on link 37 shall be extended downwardly to form a wing or flange 39' which is parallel with the link 37 and which is provided with a slot arranged coincidental with slot 38. The shaft 18 passes through both these slots, so that the link 37 is thus provided with a broad bearing on the shaft 18, to thereby insure an easy movement of the 105 sliding link 37. And to prevent lateral swinging of the link 37, the segment-shifting arm 17 may be provided with a lateral hub 17' so that the lever 17 and its hub 17' will substantially fill the space between the flange 110 39' and the main part of the lever 37.

The nature and scope of the invention having been thus indicated and its preferred embodiment having been specifically described, what is claimed as new is:

1. In a typewriting machine, the combination of a frame, a support shiftable in the frame to vary the relation between printing instrumentalities and a platen, means for guiding the support to move up and down in the frame, an arm extending fore and aft of the frame pivotally connected at one end with the support and pivotally held to the frame and having a laterally extending lug intermediate its connections with the support and frame, a pair of shift-key levers fulcrumed in the frame at the rear of the lug and overlying said lug, and a spring for normally moving the support upward, said levers being provided with parts 115 120 125 130

of different length engaging the upper side of the lug at points spaced apart longitudinally of the arm.

2. In a typewriting machine, the combination of a frame, a support shiftable in the frame to vary the relation between printing instrumentalities and a platen, means for guiding the support to move up and down in the frame, an arm extending fore and aft of the frame pivotally connected at one end with the support and pivotally held to the frame and having a laterally extending lug intermediate its connections with the support and frame, a pair of shift-key levers fulcrumed in the frame at the rear of the lug and overlying said lug, and a spring for normally moving the support upward, said levers each having an arm extending forwardly from its fulcrum under the key-carrying arm thereof and engaging the upper side of the lug, the lug-engaging arm of one lever being longer than the lug-engaging arm of the other lever.

3. In a typewriting machine, a segment-carrier and means for shifting the same embodying a pair of shift-levers and also a pair of pivotally-supported arms connected to the segment-carrier, a forwardly and rearwardly-movable case-stop, a slidable member connected to said case-stop and extending forwardly, means for guiding said member, and means operated by the shift-levers for sliding said member forwardly to different positions, for the purpose set forth.

35 4. In a typewriting machine, a segment-carrier and means for shifting the same embodying a pair of shift-levers and also a pair of pivotally-supported arms connected to the segment-carrier, a forwardly and rearwardly-movable case-stop, a slidable member connected to said case-stop and extending forwardly, means for guiding said member, and means operated by the shift-levers for sliding said member forwardly to different positions, said latter means consisting of different cam faces carried by the shift-levers.

5. In a typewriting machine, a segment-carrier and means for shifting the same embodying a pair of shift-levers and also a pair of pivotally-supported arms connected to the segment-carrier, a forwardly and rearwardly-movable case-stop, a slidable member connected to said case-stop and extending forwardly, means for guiding said member, and means operated by the shift-levers for sliding said member forwardly to different positions, said latter means embodying a beveled or cam face carried by each shift-lever, one cam face being shorter than the other, and a thrust-lug carried by said slidable member and adapted to cooperate with said cam faces.

6. Double case shift mechanism for typewriting machines comprising a support shift-

able different distances in one direction from a normal position to change case, a shiftable locking and stop member for locking the support in normal position and determining the extent of movement thereof, a pair of shift-key levers connected with the support to move the same in the same direction from normal position, and a sliding member movable a different distance by each shift-key lever and connected with said locking and stop member for shifting the same from locking position to two different positions to determine the case-shift positions to which the support is movable by the key levers.

7. In a typewriting machine, the combination of a support shiftable to vary the relation between printing instrumentalities and a platen, a pair of shift-key levers connected with the support to shift the same different distances in the same direction from normal position, a swinging shift-controlling member coöperating with the support, a member slidable fore and aft of the machine connected with said swinging member for actuating the same, and a cam on each shift key lever engaging said member, said cams being so formed as to impart sliding movements of different extent to the sliding member.

8. In a typewriting machine, the combination of a support shiftable to vary the relation between printing instrumentalities and a platen, means for normally moving the support upward, an upstanding member pivotally supported to swing fore and aft of the machine and adapted to engage the support to lock the support in its normal uppermost position, a stop carried by said member adapted to arrest the downward movement of the support at a point below its normal position, a shift-key lever connected to move the support downward, a cam on the key-carrying arm of said shift-key lever, and an actuating member pivotally connected with the upstanding member and operable by said cam for swinging said upstanding member out of locking position to a position in which said stop will arrest the support.

9. In a typewriting machine, the combination of a support shiftable to vary the relation between printing instrumentalities and a platen, means for normally moving the support upward, an upstanding member pivotally supported to swing fore and aft of the machine and adapted to engage the support to lock the support in its normal uppermost position, a stop carried by said member adapted to arrest the downward movement of the support at a point below its normal position, a pair of shift-key levers for shifting the support downward, a cam on the key-carrying arm of each lever, and an actuating member pivotally connected with the upstanding member and

shiftable different distances by said cams for swinging said upstanding member out of locking position to two different positions in only one of which said stop is effective to arrest the support.

10. In a typewriting machine, the combination of a frame, a support shiftable to vary the relation between printing instrumentalities and a platen, means for guiding the support to move vertically, a spring for normally moving the support upward, a transversely extending rock shaft journaled in the frame, a pair of rock arms held to the shaft extending fore and aft of the machine and pivotally connected with the support, a pair of shift-key levers connected with one of said arms for rocking the arms downward, a member pivotally supported on the frame to swing forwardly and rearwardly and adapted to engage the support to lock the support in its normal uppermost position, a stop carried by said member adapted to arrest the support in its intermediate position, a stop on the frame for arresting the support in its lowermost position, a reciprocable member connected with the swinging member and slidably supported on the rock shaft to move forwardly and rearwardly, and coacting cam means carried by the shift-key levers and said reciprocable member for shifting said member different distances from locking position.

11. Double case shift mechanism for typewriting machines comprising a support shiftable to change case, a pair of shift key levers, connections between the levers and support for shifting the support, a swinging member for locking the support in normal position, a stop carried by the swinging member for arresting the support in an intermediate shift position, a fixed stop for arresting the support in a maximum shift position, an actuating member pivotally connected with said swinging member, and independent cam connections between the key levers and said actuating member for shifting the swinging member a greater distance from its locking position when one key lever is operated than when the other key lever is operated to render the stop carried by the swinging member ineffective when one key lever is operated.

12. Double case shift mechanism for typewriting machines comprising a support shiftable different distances from a normal position to change case, a swinging member adapted to lock the support in normal position and carrying a stop for arresting the support in its intermediate position, a pair of shift-key levers having key-carrying arms and arms connected with the support for shifting the same from normal position, and a reciprocable member connected with said swinging member and having

independent cam connections with the key-carrying arms of the shift-levers for releasing the support when either lever is operated and setting the intermediate stop in effective position when one lever is operated and in an ineffective position when the other lever is operated.

13. In a typewriting machine, the combination of a support shiftable to change case, means for guiding the support to move up and down, a rock shaft extending transversely of the machine forward of the support, a rock arm held to the shaft and connected at its rear end with the support and provided with a laterally extending projection, a pair of shift key levers fulcrumed at the rear of the projection and provided with key-carrying arms and arms of different length extending forwardly from their fulcrums under the key-carrying arms and over said projection, a spring for normally moving the support upward, a fore-and-aft swinging member adapted to lock the support in normal case position, a stop carried by the swinging member for arresting the support in an intermediate case position, a fixed stop for arresting the support in its lowermost case position, a reciprocable actuating device connected with said member, and independent cam connections between said device and the key-carrying arms of the shift levers for swinging said member different distances from locking position to render the stop carried thereby effective on the support when one lever is operated and ineffective when the other lever is operated.

14. In a typewriting machine, the combination of a support shiftable downward different distances to change case, means for guiding the support, a rock shaft extending transversely of the machine, a rock arm held to the shaft and connected with the support, a pair of shift key levers, connections between the shift key levers and rock arm for moving the support downward, a spring for normally moving the support upward, a fore-and-aft swinging locking and shift-controlling member normally locking the support in normal uppermost case position, an actuating member pivotally connected at one end with the swinging member and slidably supported on the rock shaft to move fore-and-aft of the machine, and cam connections between said actuating member and the shift key levers for swinging the locking and shift-controlling member out of locking position to either of two different positions in one of which said locking and shift-controlling member is set to arrest the support in a case position intermediate the uppermost and lowermost case positions thereof.

15. In a typewriting machine, the combination of a support shiftable from a normal

position to intermediate and maximum case shift positions, intermediate and maximum case shift levers connected with the support for shifting the support, a swinging locking and shift-controlling member adapted to lock the support in normal position, a reciprocable actuating member connected with the swinging member, and independent cam connections between the

intermediate and maximum case shift levers 10 and the actuating member for moving said member endwise to swing the locking and shift-controlling member from locking position to two different shift-controlling positions.

This specification signed this sixth day of November, A. D. 1918.

FRANK H. ARMSTRONG.
